BALLAST FOR GASEOUS DISCHARGE DEVICES

Albert E. Feinberg and Frank S. Endo, Chicago, Ill., assignors to Advance Transformer Co., Chicago, Ill., a corporation of Illinois

Application February 23, 1952, Serial No. 273,111

6 Claims. (Cl. 315—138)

This invention relates to a ballast for igniting and thereafter providing the operating voltage for a plurality of gaseous discharge devices. Specifically the invention is concerned with the construction of the core for such apparatus, and the apparatus is especially intended for use with two gaseous discharge devices.

It often becomes necessary to provide for the ballasting of two gaseous discharge devices which are of different characteristics. Thus, for example, where the gaseous discharge devices are of different starting voltages, two ballasts are required. The invention herein is especially intended, and one of the principal objects thereof is, to provide a single ballast which will ignite and thereafter provide operating voltages for a pair of gaseous discharge devices of different characteristics.

In connection with the above object, it is also desired to provide a ballast which is extremely small, efficient, and economical.

Other objects of the invention lie in the provision of a novel core construction whereby the gaps required in the core are maintained constant and quiet; a construction providing an elongate shell-like unitary core having a central winding leg adapted to be wedged into a permanent position and provide uniform, efficient, and desirable magnetic characteristics.

Additional object lies in the provision of an electromagnetic device having a transformer and choke associated therewith but utilizing less iron than would be required were the choke and transformer separately formed.

Still a further object of the invention is to provide a novel ballast construction in which, through the medium of appropriate arrangement of the voltage senses of the various windings, certain parts of the core of the said ballast may be made considerably smaller than heretofore deemed possible at no expense to the electrical characteristics of the apparatus and without the danger of saturation effects in the core.

Many other objects will become apparent as the description of the invention proceeds, and many advantages will be brought out with the complete description and explanation of a preferred embodiment. This embodiment and various modifications thereof are illustrated in the accompanying drawings, and explained in the text hereafter, but only by way of example and not by way of limitation.

In the drawings:

Fig. 1 is an elevational view of the ballast core showing the windings thereof mounted in more or less schematic form, but in section to illustrate the construction.

Fig. 2 is a top plan view of a pair of fluorescent lamps, showing the manner in which same are arranged for maximum light, same being the type of gaseous discharge devices adapted to be used with the invention.

Fig. 3 is a schematic electrical circuit of the ballast showing the manner in which the gaseous discharge devices are connected therewith to complete the circuits thereof.

Figs. 4 and 5 are fragmentary views similar to that

of Fig. 1 but only showing the left hand end of the ballast, and illustrating different modifications of the magnetic short circuit of the core.

Fig. 6 is a schematic diagram similar to that of Fig. 3 but showing a modified form of the circuit.

As previously stated, this invention is especially intended for use in connection with apparatus for serving gaseous discharge devices of different characteristics. Such occasions may arise in connection with other than 10 fluorescent lamps, but in this case fluorescent lamps will be discussed by way of example.

Recently, the use of fluorescent lamps for lighting has attained wide-spread popularity, especially in the illumination of homes and apartments. For this purpose there 15 have been developed circular tubes capable of being associated with compact lighting fixtures. The use of multiple fluorescent lamp fixtures had posed problems with respect to lighting efficiency, for, where circular lamps of identical dimension are positioned coaxially, 20 the lower lamp masks the upper. Obviously it is impractical to dispose the lamps with their axes parallel or horizontal. Thus, fixtures were constructed for use with two such circular lamps, but with the lamps one inside of the other whereby to achieve maximum downward illumination. The lamps are arranged coaxially, but in the 25 same plane.

Obviously this can only be done with lamps of different diameters and hence different lengths. Since fluorescent lamps depend upon their dimensions for their characteristics such arrangement resulted in the bringing together in one fixture of two gaseous discharge devices of different characteristics.

Such an arrangement is shown in Fig. 2. There is illustrated inner circular fluorescent lamp 10 of lower 35 starting voltage than an outer circular fluorescent lamp 11. These can be arranged concentrically in a fixture with the usual sockets and supports (none of which is shown) to supply light. The smaller can be a 22 watt lamp, for example, and the larger a 32 watt lamp. Such 40 types of lamps are commercially available at this time, and have generally the following characteristics:

The 22 watt lamp requires a starting voltage of about 118 volts; operates at a voltage of about 62 volts; and since line voltage is sufficient to ignite the same, it requires no transformation from line voltage. Sufficient 45 reactance can be obtained through the use of a simple inductive reactor such as a choke, to ballast the same after ignition. This would of course also be the cheapest expedient.

The 32 watt lamp requires a starting voltage of about 150 volts and operates at about 83 volts. Since the starting voltage is greater than line voltage, some transformation is required to ignite the same, and obviously provision must be made for sufficient reactance to ballast 55 the same once it has become ignited.

Considering now Fig. 1 of the drawings, there is illustrated an electromagnetic device 16 embodying the invention. The core which is designated generally 15 is an important part of the electromagnetic device 16 which 60 includes the windings to be described. Since same is known popularly as a "ballast" this designation will be used interchangeably throughout this specification and the claims.

The core 15 is formed of laminations punched from 65 suitable electrical steel. There is an outer shell 17 having elongate side legs 18 and bridging ends 19, the laminations forming shell 17 preferably being integrally formed as single stampings. The shell 17 is held in assembly in any desirable manner. As shown, a suitable 70 number of laminations are stacked and riveted together by rivets 20. In the center of the shell 17, the core 15 includes a central winding leg 22. This winding leg

is also formed of punchings of electrical steel, stacked and held together by suitable rivets 23. Economically, the winding leg laminations are punched out of the center of the shell laminations at the time the shell laminations are being formed, this being done in one or more operations. The laminations could be formed of longitudinally split halves and the whole clamped together, if desired.

Integrally formed with and directed inwardly from the side legs 18 of the shell 17 are extensions 24 at the right as viewed in Fig. 1 and extensions 25 on the left. The extensions 24 are formed on the opposite sides of the winding leg and approach the winding leg 22 to abut against the rectilinear sides thereof at right angles thereto. However, there is a small gap 26 formed on opposite sides of the winding leg 22 so that the extensions 24 and the gaps 26 together form a magnetic shunt designated 27. The presence of the shunt 27 provides a window 28 at the right hand end of the ballast core 15. Obviously the window has two parts, one on each side of the central winding leg.

As for the extensions 25, these are provided with triangular tips 30 which extend into appropriate notches 31 formed in the central winding leg thereat. It will be noted that the triangular tips 30 are formed by reason of the fact that the end faces of the extensions 25 are at an angle with respect to the long dimension of the winding leg 22. These faces engage the notches 31 and extend into the winding leg 22 on a slant toward the right hand end of the core 15. Thus there is a portion 32 of the right hand edge of each of the extensions 25 that extends into the winding leg at right angles to its long dimension. This construction prevents movement of the winding leg to the left, but does not oppose movement to the right. The reasons therefor shortly will be discussed.

Inasmuch as there is no gap between the respective extensions 25 and the winding leg 22, there is formed at this position a magnetic short circuit 33 since there is no opposition to flux passing directly from the extensions 25 to the winding leg 22 and vice versa.

The presence of the extensions 25 gives rise to window 34 on the right side of the magnetic short circuit 33 and the window 35 on the opposite side thereof. Obviously the window 34 is defined by the extensions 24 and 25, and like the windows 28 and 35 is formed of equally shaped parts on opposite sides of the winding leg.

At the left hand end of the core 15, on the inner surface of the bridging end 19 there is a recess which may be formed either by working the metal out of the side face of the end 19 or by punching same out during the formation of the respective laminations. The left hand end of the leg 22 terminates just even with the normal inner face of the end 19 and hence there is formed a non-magnetic gap 37 at this point.

It will be seen that there is no magnetic connection between the central winding leg 22 at its left end and the shell 17, the said winding leg depending for support on the connection between the extensions 25 and the notches 31. As for the right hand end of the winding leg 22, same is intimately and matingly engaged with a suitable notch formed in the right hand end 19 to form the tight juncture 38. The efficiency of the electromagnetic device 16 calls for this juncture always to be tight so that the passage of magnetic flux is in no way hindered thereby.

The advantages of the notched connection of the magnetic short circuit 33 between the triangular ends 30 and the notches 31 are of importance. In the first place, when the windings of the device are mounted on the central winding leg, and the leg pressed into the core, this notched connection properly seats the winding leg as it is pressed home into the shell 17 and accurately fixes the width of the gaps 26 and 37. The second important advantage is that any strain caused by magnetic flux attempting to

move the central winding leg 22 would have a tendency to cause the central winding leg to move only to the right. This is because the slanted end faces of the extensions 25 present less resistance to movement to the right than the portions 32 present to the left. Movement to the right can do nothing more than more firmly seat the juncture 38, but because of the juncture such movement is practically impossible. There is a binding effect which decreases vibratory noises at juncture 38.

Since the portions 32 of the sides of the extensions 25 are at right angles to the long dimension of the central winding leg 22, movement to the left is impossible and the width of the gap 37 can be maintained with great accuracy. There is little tendency for spreading of the shell 17 in the center which might cause widening of the gaps 26, because the movement of the central winding leg 22 to the right must be quite marked in order for the extensions 25 to move outwardly any perceptible amount.

In the interests of preventing noise, the left hand end of the central winding leg 22 may be provided with a small centrally located integrally formed teat or protuberance 40 adapted to engage in a suitable notch in the bridging end 19. This provides the gap 37 with a central support. In Fig. 4 this modification is shown, and there is also shown a modified form of extensions 25' which do not have triangularly shaped ends but instead closely abut against the sides of the central winding leg to form the magnetic short circuit 33. The physical support of both ends of the central winding leg 22 decreases the necessity for using the expedient shown in Fig. 1 to prevent any possible movement of the central winding leg to the left.

A further modification of the extensions is shown in Fig. 5. Here the extensions 25" are rounded and extend into notches 31" of identical shape formed in the central winding leg. The left hand end is shown without support since the magnetic short circuit is a rather rigid connection between shell and winding leg. The unequal resistance to movement which is characteristic of the embodiment of Fig. 1 is not available by this construction.

The circuit of the ballast is shown in Fig. 3 or Fig. 6 in which, in order to render the drawings more lucid, the lamps 10 and 11 have been diagrammatically developed so that they have the appearance of the conventional rectilinear lamps. The core is designated at 16 by the usual iron core convention. The magnetic short circuit 33 and the magnetic shunt 27 are geometrically located in proper relation to their actual physical location.

The primary winding P is mounted in the central window 34, with the secondary winding S in the window 28 on the right hand end of the core 15 and the choke winding Ch in the window 35 on the left hand end. In Fig. 1 the windings are shown in section, and it should be obvious that they surround the central winding leg 22 in this particular kind of core. Efficient production is preferably achieved by pre-forming the respective windings, mounting them upon the central winding leg in proper position and relation one to the other, and then forcing the assembled center into the shell 17.

Examining the circuit of the device 16 shown in Fig. 3, we see that the lamps 10 and 11 are each shunted by a conventional starter switch S₁ for causing ignition thereof. The lamp 10, which is the smaller of the two is connected in series with the choke winding Ch, and together with the choke winding connected across the primary winding P. Winding Ch is in lead 40 which connects with right side of primary winding P. Lead 41 connects with lead 42 which connects with left side of primary P. The primary winding P is energized from a conventional line and has terminal leads 44 and 45 to permit such connection. For the examples described the line will be a 118 volt, 60 cycle A. C. power source.

The second winding S is connected in auto-transformer relation to the primary winding P, and its left hand terminal is connected by lead 46 to the right side of the pri-

mary P, while its right hand terminal connects by lead 47 to the larger lamp 11. Lead 48 connects left end of lamp 11 to common conductor 42 and through the same to the primary winding P.

Since there is a magnetic short circuit 33 between winding Ch and the rest of device 16, when the primary winding P is energized, no flux will affect winding Ch. Until lamp 10 ignites no current flows through Ch, and the only voltage to which lamp 10 is subjected is 118 volts from the primary. We may disregard the starting circuit with switch S and the initial minute flow of current for heating up the filaments. Note that the winding Ch and the surrounding portions of the core 15 together with gap 37 form a high inductance choke. This choke functions after the lamp 10 is ignited, serving to limit current flow therethrough.

The energizing of the primary winding P, however, induces a voltage in winding S, since same are magnetically coupled, so that the ignition voltage across the lamp 11 during starting is the sum of voltages of P and S. Loose coupling between P and S provides high leakage reactance after current flows so that the winding S serves to ballast lamp 11 and limit current flow therethrough.

It will be seen that this construction provides a ballast for operating two gaseous discharge devices having different characteristics in which ballast there are achieved considerable savings in both material and labor. Only one article is to be produced and handled, and the volume occupied is considerably less than it would be were two electromagnetic units used.

The construction which has been described is novel in another manner which gives rise to great savings. The outline of the laminations illustrated in Fig. 1 is exactly proportional to the dimensions of an actual commercially produced example of the device. The overall length of the shell 17 was exactly five inches, and the ballast was intended for igniting and operating the lamps whose characteristics have been set forth herein. With this device, it will be seen that the width of the extensions 24 is about one-half inch, and the width of the extensions 25 is about one-third of an inch. This latter dimension is surprising, since theoretically, the flux which is produced during operation by both the primary P and the choke winding Ch will thread the magnetic short circuit 33. This concentration of flux will tend to saturate the core at this point and distort the wave shape. Good engineering would dictate a width of the extensions 25 of more than twice that shown.

We have found that the width of the extensions 25 can be made quite small without in any way affecting the core saturation by the expedient of arranging the windings P and Ch so that their respective fluxes are in phase. This is done by connecting the windings appropriately in a manner well known in the art. The flux arrows in Fig. 1 show the principal flux Fc of the choke winding Ch pointed to the right and splitting at the magnetic short circuit 33 with the flux threading the short circuit passing outwardly of the central winding leg 22. The primary flux Fp is shown directed inwardly of the central winding leg and joining at the center thereof to form the arrow directed to the right. Obviously the primary and choke fluxes while in phase through the central winding leg are in opposition in the extensions 25. The resultant flux density will therefore be considerably smaller through the magnetic short circuit than if the flux patterns were arranged to enforce instead of buck one another.

Although there is no magnetic relation required between the right and left hand parts of the ballast, the existence of the relation described gives rise to many advantages we have enumerated. Furthermore, notwithstanding the decrease in the size of the extensions 25, other constructional features have been pointed out which are considered of importance.

Measurements made in the commercial version of the

invention relative to flux density show that the theory set forth above is probably a valid explanation of what occurs in the core. A table of such measurements has been set forth below giving the flux density in Gauss in various parts of the core under different circumstances.

	A	B	C	D
Both lamps operating-----	12,400	6,280	10,000	10,700
Lamp 10 off-----	12,400	13,850	0	500
Lamp 11 off-----	830	7,540	10,000	10,400

In the above table, the places at which the measurements were taken are marked in Fig. 1. A represents flux passing through the shunt 27, B represents flux threading the short circuit 33, C represents flux in the outer arm of the choke core, and D represents total choke flux. Flux density approaching saturation is of the order of 18,000 Gauss, and it will be seen from the table that this is never reached in the ballast. The most significant part of this table is column B. Note that when only the lamp 10 is operating the flux density in the extensions 25 is 7,540 Gauss. When only the lamp 11 is operating the flux density at the same place is 13,850 Gauss. When both lamps are operating, the resultant flux density in the extensions 25 is the difference instead of the sum of the fluxes produced by the two parts of the device, and hence the extensions can be made very narrow.

The dimensions of the example discussed can be obtained by simple proportions from the single dimension given that the length of the lamination of Fig. 1 is five inches. The lamination was formed of ordinary electrical steel of a gauge usual for such size ballasts, and the stack was three quarters of an inch high. The choke winding Ch and the secondary winding S were each formed of 740 turns of No. 27½ wire. In the design of a ballast of this type, the inductance of the winding S must be sufficient to ballast the particular lamp 11 used. In the specific example, the number of turns necessary to supply the desired secondary inductance in the event the entire primary is used as a source of starting voltage would subject the lamp 11 to too great a starting voltage. Hence, only a part of the primary was used for supplying starting voltage as shown in the modified circuit, Fig. 6. The left hand end of the secondary S, instead of being connected by way of lead 46 to the right hand end of the primary P and joining the terminal lead 45 thereat, was instead tapped in some windings short of the end, as for example by the lead 46', there being no other connection of the left end of S to the primary P under such circumstances. The primary winding P in this case was formed of 750 turns of No. 30 wire and 190 turns of No. 27½ wire, with the secondary winding S tapped in at the junction of the two parts of the primary. Obviously the heavier wire is required since all current passes through the smaller section of the primary.

It is desired to point out that the specific proportions and dimensions used are capable of wide variation for the purpose of adapting the invention to use with other types of gaseous discharge devices. In the case of certain advantages of the invention, the configuration of the core as set forth need not be followed, and in other cases, different variations are possible without departing from the spirit of the invention.

What we desire to secure by Letters Patent of the United States is:

1. In a ballast of the character described and including a single unitary core having an outer shell and a central winding leg, said central winding leg terminating short of the shell end at one end of the said leg thereat a non-magnetic gap and engaged intimately with the shell at the second end thereof, a pair of aligned extensions of the sides of the shell integrally formed there-

with and engaging against the central winding leg from opposite sides thereof between said ends and forming thereby a magnetic short circuit separating the core into two parts, a winding mounted on the central winding leg in the part having the said gap and adapted to serve as a choke winding, and a pair of windings mounted on the central winding leg in the second part and adapted to serve as a transformer, and means for preventing longitudinal movement of the central winding leg from varying the gap at said first end comprising notches formed in the said winding leg and having the ends of the said extensions engaged in the said notches, said notches being substantially non-symmetrical V-shaped with the sides of unequal length and having the ends of the extensions conforming.

2. In a ballast of the character described and including a single unitary core having an outer shell and a central winding leg, said central winding leg terminating short of the shell end at one end of the said leg thereat a non-magnetic gap and engaged intimately with the shell at the second end thereof, a pair of aligned extensions of the sides of the shell integrally formed therewith and engaging against the central winding leg from opposite sides thereof between said ends and forming thereby a magnetic short circuit separating the core into two parts, a winding mounted on the central winding leg in the part having the said gap and adapted to serve as a choke winding, and a pair of windings mounted on the central winding leg in the second part and adapted to serve as a transformer, and means for preventing longitudinal movement of the central winding leg from varying the gap at said first end comprising notches formed in the said winding leg and having the ends of the said extensions engaged in the said notches, said extension ends having their faces formed on a plane slanted inward of the central winding leg in a direction toward the second end of the winding leg whereby the sides of the said extensions will be of unequal length with the longer side extending substantially into the winding leg to oppose movement of the leg tending to close the gap.

3. In a ballast of the character described and including a single unitary core having an outer shell and a central winding leg, said central winding leg terminating short of the shell end at one end of the said leg thereat a non-magnetic gap and engaged intimately with the shell at the second end thereof, a pair of aligned extensions of the sides of the shell integrally formed therewith and engaging against the central winding leg from opposite sides thereof between said ends and forming thereby a magnetic short circuit separating the core into two parts, a winding mounted on the central winding leg in the part having the said gap and adapted to serve as a choke winding, and a pair of windings mounted on the central winding leg in the second part and adapted to serve as a transformer, and means for preventing longitudinal movement of the central winding leg from varying the gap at said first end comprising notches formed in the said winding leg and having the ends of the said extensions engaged in the said notches, said extension ends having their faces formed on a plane slanted inward of the central winding leg in a direction toward the second end of the winding leg whereby the sides of the said extensions will be of unequal length with the longer side

extending substantially into the winding leg to oppose movement of the leg tending to close the gap, the second side of each extensions intersecting the plane substantially at the edge of the central winding leg so that resistance to lengthwise movement of the central winding leg towards the second end will be less than the resistance in the opposite direction of movement.

4. In combination, a pair of gaseous discharge devices of different starting and operating characteristics, a source of A. C. power of sufficient voltage to ignite one device but insufficient to ignite the second device and a ballast for supplying current to the devices from said source comprising an elongate outer shell and a central winding leg, a primary winding, a secondary winding and a choke winding all mounted on the winding leg, the choke winding being connected in series with the one device and together therewith connected across the primary, the primary and secondary windings being connected in autotransformer relationship with the second device, said shell having a pair of extensions integral with opposite long sides thereof and terminating against the central winding leg to form a magnetic short circuit therebetween, the choke and primary windings being positioned on opposite sides of the extensions and their voltage senses being additive during operation of the gaseous discharge devices to produce flux travelling through the central winding leg in the same direction, but through the extensions in opposite directions such that the flux density in the short circuit will be considerably less than the sum of flux densities due to the respective windings considered separately, said primary winding having leads connecting same to said source, the central winding leg having one end engaging the shell in closed magnetic circuit relation at the end adjacent the secondary winding and having the opposite end spaced from the shell to form an air gap adjacent the choke winding.

5. A construction as described in claim 4 in which said shell has a second pair of extensions integral with opposite long sides thereof positioned between the primary and secondary windings and each terminating short of the winding leg to provide a non-magnetic air gap thereat, whereby to provide loose coupling between the primary and secondary windings and high leakage reactance for ballasting said second device during operation thereof.

6. A construction as described in claim 5 in which the extensions between said primary and choke windings are engaged in notches provided in said central winding leg to prevent lengthwise movement of said center winding leg.
